ORE-ROASTING OVEN

Henry H. Harris, Champaign, Ill.

Application October 5, 1942, Serial No. 460,909

12 Claims.

(Cl. 266—19)

My invention relates to ore roasting ovens, and in particular, to roasting ovens within which retorts or other ore containers are disposed during the roasting of the ore, or may be used for reduction treatment of metals as magnesium.

Retorts commonly used in roasting processes are relatively elongated, hollow cylindrical tubes or high heat and corrosion resisting metal alloys. Their cost, and the present-day scarcity of the necessary materials makes their protection and continuously efficient operation important, and the furnace of my invention is well adapted not only to protect the retorts against the destructive effects of furnace operation, but also to insure operation at peak efficiency. Their exaggerated length in respect of diameter and wall thickness is dictated by the necessity for uniform heat application to the interior thereof, and they must be protected during expansion and contraction; I have found, in order to prevent premature cracking, sagging and consequent failure.

According to one well-known process, the retort is charged with ore and subjected to heat within the furnace. The metal volatilized by the heat moves to the cooler or charging end of the retort, as is customary, at which point it is condensed. The retort is periodically opened, the condensate removed, and the spent ores taken out. The retort is refilled with a new charge and again subjected to heat. The weight of the load is originally distributed over that portion of the retort which is within the furnace. As a result of the heat treating process, the metal is volatilized from the ore and moves toward the cooler portion of the retort, outside of the furnace, where it is condensed. There is thus a shifting of the weight within the retort, from one end thereof to the other. The retorts are thus not only subjected to the intense heats and thermal shocks incident to the cyclic nature of the process, but also to the destructive effects of expansion while loaded under heat, and the subsequent contraction when the heat is abated.

The main object of my invention, therefore, is the provision of an ore roasting oven in which means are provided to support and protect the ore-containing retorts during the entire roasting process.

Another object of my invention is the provision of an ore roasting oven with means therein to support a plurality of ore-containing retorts at a plurality of points, and means are provided at these points to compensate for changes in the position of the retort.

A further object of my invention is the provision of an oven of the character described wherein means are provided inside and outside of the oven to support the retorts at a constant level.

A still further object of my invention is the provision of means, in an ore roasting oven, to support a plurality of retorts therein each at a plurality of points, and means to permit the retorts to expand and contract under the influence of the supporting means.

A still further object of my invention is the provision, in an ore roasting oven, of a plurality of piers, which may be evenly spaced along the furnace length, having retort supporting means thereon and therethrough.

A still further object of my invention is the provision, in an ore roasting oven, of a plurality of saddle-topped piers to support retorts within the oven, the saddles being laterally yieldable to compensate for changes in retort expansion and contraction.

Other and further objects of my invention will be apparent from the following description of an illustrative embodiment, and still others will be specifically pointed out. For convenience, I will describe my invention in respect of an apparatus for the roasting of ores or it may be used for reduction of magnesium from magnesium-containing ores, although my invention is not to be limited except by the scope of the annexed claims.

In the drawings annexed hereto, forming a part hereof,

Fig. 1 is a longitudinal vertical section through one form of oven constructed according to and embodying my invention, several of the retorts being shown in elevation;

Fig. 2 is a transverse vertical section on the line 2—2 of Fig. 1;

Fig. 3 is an end elevational view of my invention, as seen from the charging end thereof, the right side of Fig. 1;

Fig. 4 is a top plan view, partly in section, of one form of support cradle constructed according to and embodying my invention;

Fig. 5 is a section on the line 5—5 of Fig. 4; and

Fig. 6 is an end elevation thereof, partly in section.

The oven of my invention is indicated generally by reference numeral 10, and comprises a generally cylindrical casing 12, of high heat and corrosion resisting material, which casing is closed at both ends thereof. The inner surface

55 of the oven is lined with suitable refractory ma-

terial, fire brick or the like, as indicated at 14 capable of withstanding extremely high temperatures, temperatures in excess of that required for the roasting process. A suitably shaped support structure 16 is provided, on which 5 the oven is mounted.

The interior of the oven is gas heated, via annular external manifolds 18, 18, having offset tubes 20 jetting into the oven interior through suitable openings 22, 22, the jets 21, 21, being 10 angled to produce a swirling flame effect around the interior of the cylindrical chamber 24.

Within the interior of the oven chamber 24, I erect a plurality of piers 26, 26, each of which may extend completely across the chamber, and evenly spaced apart along the length thereof (see Figs. 1 and 2). Piers 26, 26, are built of fire brick or other suitable heat resisting material, and rise to just below the center line of chamber 24.

The use of piers, as 26, evenly spaced along the furnace length may provide brute support for the retorts 30, 30, but this mere vertical line support for the retorts is not sufficient under expansion and contraction, and I have, therefore, devised means to provide lateral support as well as vertical line support for the retorts within my furnace. I provide a number of openings, as 28, 28, through the piers 26, 26, said openings 28, 28, being formed in longitudinal alignment along the line of oven length. As will be seen in Figs. 2 and 3, my oven may be constructed to receive therewithin seven retorts 30, 30, and I arrange them in spaced-apart relation to permit free flow and ready access of heat thereto. Three of the retorts are substantially on the center line of the furnace, with two above and two below, staggered in vertical alignment.

Atop the piers 26, and on the bottoms of openings 28, 28, I place saddles or cradles 50, 50. The saddles comprise metallic castings, having flat floor portions to rest atop the furnace piers and the pier openings; leg members 52, 52, depending from the sides thereof to straddle the piers and secure the device thereof; raised sides 54, 54, and concavely curved bed portions 56. A rectangular openwork frame 60 is provided for each saddle, the ends 62 of which frame are straight. The sides 64 of frame 60 are downwardly curved to conform to the curvature of bed 56, and the frames are of such size as to overlie and rest directly upon the saddles 50. Frame and members 62, 62, are provided with a plurality of aligned apertures 66, 66, and a similar plurality of wire cables 68, 68, of high heat resisting material are threaded therethrough across the frame and secured to the frame sides 62, 62, as by welding or otherwise, as indicated at 70. Cables 68 are longer than the distance between the end members of frame 60, and sag downwardly to conform to the curvature of the frame side bars 64 and saddle bed 56. The construction illustrated in Figs. 4 to 6, inclusive, describes the type of saddle placed across openings 28 through piers 26. The three saddles mounted atop piers 26 are substantially identical, differing only in having connecting links 80, 80, and the two topmost saddles are also similar in construction, except that they are mounted atop stub piers 92, 92, which extend upwardly from the top of pier 26, and are connected by a link 99.

The elongated retorts 30 are supported within the oven by the saddles 50, 50, aligned along piers 26. The cables 68 on the saddle frames 60 take the retort weight, and are deformable to some 75

slight extent to cushion the retort and yieldably support same against deformation under heat and weight. Each saddle is independent of the other, except that originally they are all mounted on a common level.

The front end 70 of each retort projects out of the oven and through suitable openings 72 in the front end cover 14 thereof. A hanger bar 76 is provided for each retort, having a stirrup member 78 at the bottom thereof to receive the retort therethrough. The upper end of each hanger 10 76 is pivotally connected to a rod 100 extending along the furnace length and secured atop the oven. Rods 100, 100 are pivoted near the front ends thereof, and are provided with counterweights C. A number of viewing openings P may be formed in the rear end wall 16, and also in the sides of the oven proper, so that the interior of the oven and the actions of the retorts may be inspected during the process, and the counterweights shifted back and forth along rods 100 to raise or lower the retorts in response to oven conditions.

As seen in Fig. 1, the retorts are supported 25 mainly by the saddle-topped piers. The extending portions 70 are supported by hanger bars 76. There is preferably no contact between the retort and the oven end 14, through which the retort projects out of the oven.

30 A tapered collar 97 is provided, having longitudinal slits 99, and fitted over each retort at the opening in the oven end 14 (see Fig. 1). This collar acts to absorb the temperature differential between the parts of the retort in and out of the oven at the zone of change.

35 My saddles 50, with their cable loops, permit the retorts to move laterally under expansion and contraction. The deformability of the cables provides a cushioning seat for the loaded retorts which are thereby supported vertically and in a lateral direction. The counterweight system at the front of the oven permits adjustment of level for optimum distribution of retort weight throughout the reducing process.

Having described my invention, what I claim and desire to secure by Letters Patent is:

1. In a roasting oven of the character described, a plurality of longitudinally disposed retorts within the oven, means to support each thereof at a plurality of points within the oven, and heat responsive means to permit the expansion and contraction of the retorts under the influence of the supporting means, said supporting means being adjustable in response to heat conditions within the oven.

2. In a roasting oven of the character described, a plurality of retorts disposed within the oven and having a portion of each retort projecting laterally out from the oven, and means to support each retort at a plurality of points, some of which supporting means are within the oven and others of which are without the oven, all of said supporting means permitting lateral movement of the retorts in response to heat conditions within the oven.

3. In an oven as in claim 2, the supporting means without the oven being vertically adjustable to compensate for movement of the retorts within the oven.

4. In an oven of the character described, a retort, means within and without the oven to support said retort, the means within the oven supporting the retort from below, and the means without the oven supporting the retort from

above, both means being adjustable to compensate for heat conditions within the oven.

5. An oven as in claim 4, in which the supporting means within the oven permit lateral movement of the retort in both directions in response to heat conditions within the oven.

6. An oven as in claim 4, in which the supporting means without the oven also permit lateral movement of the retort and are vertically adjustable to compensate for changes in the 10 horizontality of the retort.

7. In a roasting oven of the character described, a plurality of retorts horizontally disposed within the oven, means to support each thereof at a plurality of points, and means to permit change in the horizontality of the retorts under the influence of the supporting means.

8. In an oven of the character described, a retort and means to support same within the oven comprising a plurality of piers, means thereon to yieldably receive the retort while permitting lateral movement thereof under expansion and contraction.

9. In an oven of the character described, a retort and means to support same within the oven, said support means comprising a plurality of piers arranged lengthwise of the oven, and having saddles thereon, to yieldably receive the retort while permitting lateral movement thereof

under expansion and contraction, said saddles being shaped to receive the retorts and having cushioning members extending thereacross to reciprocatably shift and contract in response to retort movement.

5 10. In an oven of the character described, a plurality of retort-supporting saddles, each saddle comprising a shaped base member to receive the retort, and having retort-weight cushioning means stretching across the frame.

15 11. In an oven of the character described, a plurality of retort-supporting saddles, each saddle comprising a shaped base member to receive the retort, and having retort-weight cushioning means stretching across the frame, the cushioning means being yieldable to absorb retort weight to some extent while permitting lateral movement of the retort in respect thereof.

20 12. In an oven of the character described, a plurality of retort-receiving saddles, in longitudinal alignment, each saddle comprising a shaped base member to receive the retort thereon and having a similarly shaped frame fitting thereover, the frame having a plurality of transversely arranged retort cushioning members, the cushioning members being conformable to the retort shape and laterally shiftable to permit retort movement under expansion and contraction.

HENRY H. HARRIS.
